UNITED STATES PATENT OFFICE.

WILLIAM P. HORNBUCKLE AND ROBERT F. CRAIG, OF STANLEY, NORTH CAROLINA.

BEAM WARPER.

Application filed September 9, 1926. Serial No. 134,401.

The invention has relation to beam warpers; that is to say, to warping machines of the class employed for winding upon a beam a series of yarns or threads assembled 5 in the manner, etc., usual in the case of the preparation of a warp for use in weaving.

In practice, a receiving-beam in a beam warper is rotated, for the purpose of winding the series of yarns or threads upon it, 10 through contact between the periphery of the wound mass upon the beam and the periphery of a power-driven friction-drum. This peripheral driving engagement is utilized because it produces a rate of winding which is 15 uniform throughout all stages in the increase of diameter of the wound mass, avoiding gradual increase in the density of the wound mass from the center outward.

In some cases, for the purpose of enabling 20 yarns or threads to be wound into a mass of predetermined density, either firm and compact or soft and porous, whichever may be desired, beam warpers are equipped with means for giving to the yarns or threads as 25 they are wound on the beam a definite state of tension which will secure the desired density of the wound mass. This means consists of a roller with which the yarns or threads engage just prior to being wound on the 30 beam, and which is driven with a surface-speed bearing such relation to the surface-speed of the wound mass that the rate at which the yarns or threads are wound upon the beam will impart the required tension 35 to the yarns or threads as they wind upon the beam, and thereby produce the desired condition in the wound mass.

The invention consists in a beam warper having a friction-drum, a positively-driven 40 tension-controlling roller, and improved means for driving the said roller with capacity for regulation at will of the ratio between the surface-speed of the said roller and that of the friction-drum. More specifically 45 stated, the invention consists in a beam warper comprising a friction-drum for the actuation of a receiving-beam or the like and a tension-controlling roller, and characterized by having the tension-roller operatively 50 combined with the friction-drum by means of a direct driving train extending from the latter to the former and including manually-adjustable speed-varying means by which the 55 ratio of the surface-speed of the tension-controlling roller with respect to that of the friction-drum may be regulated at will

through manually-effected adjustment in the connections between the friction-drum and the said roller.

An illustrative embodiment of the invention is shown in the accompanying drawings, in which latter,—

Fig. 1 is a view in side elevation of a warper containing the said embodiment.

Fig. 2 is a view thereof in vertical section 65 in a plane parallel with the side-frames.

Fig. 3 is a partly-sectional elevation of the speed-varying means, on a larger scale than Figs. 1 and 2.

Fig. 4 is a partial front elevation of the 70 warper.

In the drawings, a friction-drum is shown at 1, with a receiving-beam in working relation therewith, and a tension-controlling roller is shown at 2. The shaft 11 of the friction-drum 1 is shown mounted as usual in bearings 12, 12, in connection with the lower portions of the side-frames 3, 3, of the machine. The journals of the tension-controlling roller 2 are mounted in bearings in connection with the upper portions of the said side-frames. In practice, rotary motion is imparted to the said friction-drum by means of power applied to the shaft 11 through suitable driving connections (not shown). The 85 direct driving train by means of which the tension-controlling roller is rotated from the friction-drum is shown in Figs. 1, 3, 4 and described hereinafter.

For controlling the position of the receiving-beam so as to hold its barrel 4, Fig. 2, in proper working relation with respect to the periphery of the friction-drum, the journals of its shaft 5 in this instance are shown seated in open-topped bearings at 6 in connection with forwardly projecting arms 61 of levers which are mounted pivotally at 62 upon the side-frames 3, 3. By reason of the levers being capable of swinging around the pivots or fulcrums 62 the beam is enabled to 100 gravitate toward the friction-drum so that the periphery of the beam-barrel, or that of the mass of yarns or threads wound on such barrel, may rest in contact with the periphery of the friction-drum. Also, the beam is enabled to move away from the shaft 11 in proportion, as the wound mass increases in diameter. The rearwardly extending arms 621 of the said levers are shown as having weights 63, 63, Fig. 1, removably applied 110 thereto for the purpose of partly counterbalancing the combined weight of the beam

and the load 7 of yarns or threads wound thereon, so as to diminish the force with which the exterior of the wound mass presses against the periphery of the friction-drum, 5 and thereby guard against too much compression of the wound mass as the yarns or threads 8 are wound upon the beam. The weights 63, 63, may be added to from time to time in proportion as the size and weight 10 of the wound mass increase, in order to equalize the counterbalancing function throughout the filling of the beam, or for such purpose may be shifted on the lever-arms 621 away from the lever-pivots or fulcrums 15 62. This weighted-lever arrangement is not included in the present invention.

The tension-controlling roller 2 is located near the position of the receiving-beam so that it controls the tension of those portions 20 of the yarns or threads which are intermediate the roller itself and the place at which the yarns or threads are received by the periphery of the wound mass on the beam. Guide-rolls 9, 9, Fig. 2, at the rear and front, respectively, of the tension-controlling roller cause the yarns or threads to encircle a substantial portion of the periphery of the said 30 roller, to ensure more effective engagement between the yarns or threads and the said periphery, and enable the roller to control the tension of the yarns or threads more efficiently. Those elements of the warper which are located at the rear of the tension-controlling 35 roller, with which the yarns or threads engage before reaching the said roller are or may be as usual or as preferred.

Referring, now, to the direct driving train 40 connecting the tension-controlling roller with the friction-drum and through which the latter drives the former, such train comprises, in the form thereof which is illustrated in Figs. 1, 3 and 4 of the drawings, the following elements:

A spur-gear 13 is fixed upon one end of the 45 shaft 11 of the friction-drum. A spur-pinion 14 is mounted upon a support 15 in connection with the adjacent side-frame 3, and in engagement with spur-gear 13. A cone-pulley 16 in fixed connection with the said spur-pinion 14 is mounted upon the said support 15 to turn in unison with such spur-pinion. A second cone-pulley 17, and connected spur-pinion, 18, are mounted to turn in unison 50 upon a support 19 in connection with the said side-frame. A belt, 20, applied to the two cone-pulleys serves for transmitting rotary motion from the first cone-pulley, 16, to the second thereof, 17. A carrier-pinion 191 is mounted upon a support 201 in connection 55 with the said side-frame, and a spur-pinion 21 is fixed upon the adjacent journal of the

tension-controlling roller 2, the said carrier-pinion being in engagement with the two spur-pinnions, 18 and 21.

Through the elements just described, the 65 tension-controlling roller is driven from the friction-drum itself, so that there is a convenient readily perceived relation between the surface-speeds of the two. The ratio of the surface-speed of the tension-controlling 70 roller with respect to that of the friction-drum may be varied at will through a shift of the cone-belt 20 in the direction of the length of the cones. This shift is provided for in the present instance by means of belt-shifting devices comprising a shifter-fork, 22, through which the cone-belt passes, and a fork-shifting screw 23 provided with a hand-wheel 24 through which it may be turned manually in effecting adjustment of the shifter-fork lengthwise of the cones. At 25 is 75 shown a guide-bar upon which the shifter-fork slides as it is moved inward and outward by means of the adjusting screw 23.

Within the scope of the invention as defined in the following claims, the constructional embodiment of the invention may be modified more or less in practice.

What is claimed as the invention is:—

1. In a beam-warper including a friction-drum mounted to rotate in stationary bearings and adapted for the actuation of a receiving beam or the like on which friction-drum the said receiving drum rests so as to derive support therefrom in addition to being actuated thereby, and a tension-controlling roller adjacent the winding-point in the machine, the combination comprising the said friction-drum, the said tension-controlling roller, and a driving train through which the roller is driven from the friction-drum, and manually-adjustable speed-varying means between the friction-drum and the roller by which the ratio of the surface-speed of the tension-controlling roller with respect to that of the friction-drum may be regulated at will through manually-effected adjustment in the connections between the friction-drum and the said roller. 105

2. In a beam warper, the combination with a beam-actuating drum mounted to rotate in stationary bearings, and a tension roll for the yarns, of a cone geared to the said beam, a second cone in driving connection with the said tension roll, a cone belt connecting the said cones, and means for adjusting said cone belt upon the cones to vary the relative peripheral speed of the tension roll with reference to that of the drum. 110
